DISPLAY CASE

Frederick S. Holderle, Harvey C. R. Holderle, and
Norbert F. W. Holderle, Rochester, N. Y.

Application June 26, 1952, Serial No. 295,798

3 Claims. (Cl. 312—117)

1

This invention relates to a display case, with more particular reference to the type of case adapted for containing candy, nuts, and the like in a loose state and has for its purpose to afford a construction that is economical to manufacture, which can be readily assembled, and which presents an attractive and effective display of the goods in the case.

In a more particular aspect, the invention has for its object to provide a construction in which loose candy or other merchandise can be housed in bins in such a manner that the candy in a particular bin is afforded a maximum display at the front of the case while portions of the candy can be removed from the rear of the bin when sold without materially disturbing or affecting the position of the display body of material at the front, and at the same time making it easy for an attendant to mix and freshen the entire contents of a bin when refilling at the beginning of each day or as required.

A further purpose of the invention is to afford a novel arrangement in which a maximum area of merchandise is displayed at the front of the case in proportion to the total volume of contents of a bin and accomplishing this by providing the bottom of the case with a downwardly inclined portion at its front end which functions to hold a large mass of merchandise against the transparent front wall when the contents in the rear of the bin have been partially depleted.

Still an additional object of the invention is to provide a removable partition member that can quickly be adjustably positioned to provide a bin of any desired size and which when in position is retained securely and cooperates with the bottom and transparent front panel of the case to afford a container with a maximum display area.

Another purpose of the invention is to afford a display case that can be readily cleaned, thus enhancing its sanitary characteristics, and in which the partition members can be instantly changed to different positions and when once adjusted are held firmly without the necessity of any removable fastening devices.

To these and other ends, the invention consists in the construction and arrangement of parts that will appear clearly from the following description when read in conjunction with the accompanying drawings, the novel features being 50 pointed out in the claims following the specification.

In the drawings:

Fig. 1 is a view in side elevation illustrating a show case constructed in accordance with a 55 preferred embodiment of the invention;

Fig. 2 is a front elevation of the same;

2

Fig. 3 is an enlarged detail sectional view taken generally on line 3—3 of Fig. 2, looking in the direction indicated;

Fig. 4 is an enlarged detail sectional view on line 4—4 of Fig. 3, looking in the direction indicated;

Fig. 5 is an enlarged detail sectional view in the same plane as Fig. 3, and taken at the rear of the case and partition member;

Fig. 6 is an enlarged detail sectional view on line 6—6 of Fig. 5, looking in the direction indicated;

Fig. 7 is a detail perspective view of one of the retaining bars, which are located at the front and rear of the case, with reference to the partition member;

Fig. 8 is a top plan view of one of the partition members;

Fig. 9 is a view in side elevation of the same;

Fig. 10 is a view in front elevation of the same, and

Fig. 11 is a diagrammatic side elevation similar to Fig. 1, showing the position of the display body of candy at the front of the case when a portion of the contents at the rear has been removed.

Referring more particularly to the drawings in which like reference numerals throughout the several views refer to the same parts, the case includes preferably a metal framework embracing inclined front portions 1 which support a transparent or glass panel 2, horizontal top portions 3 which support a horizontal transparent or glass panel 4 at the top, rear vertical supporting portions 5, and bottom side walls 6 that preferably extend to points adjacent the front and rear supports 7 and 8 upon which the metal case is mounted, see Fig. 1.

The front support 7 is somewhat lower than the rear support 8 as shown, to accommodate the front portion of the case which extends to a point lower than the rear portion owing to the front part of the bottom of the case being at a lower point than the main body or horizontal portion of the bottom wall. The bottom wall which is formed integral with the side portions or permanently connected thereto in any suitable fashion, is preferably of metal and includes a horizontal portion 9 that has at its forward end a downwardly inclined portion 10 which forms an acute angle with the transparent panel 2 and terminates in a dished or arcuate-shaped portion 12 at its front end, affording a longitudinally arranged gutter that can be readily cleaned to maintain the case in a sanitary state.

The dished portion 12 at the front end of the bottom wall terminates in a vertical portion 13 to which is attached a front wall 14 that is connected to a horizontal portion 15, which rests

upon the forward support 1, see Figs. 1 and 3, and is connected to a downwardly extending portion 16 terminating in a horizontal flange 17 that underlies a wooden base 18 to which the metal frame is attached. The horizontal portion 9 of the bottom wall terminates at its rear end in a vertical flange 19 to which is secured a rearwardly and upwardly inclined portion 21 terminating in a downwardly inclined portion 22 and tray 23 in rear of the supports 5 for convenience in handling candy or other materials when placing them in or removing them from the display case.

In order to house candy, nuts, or other materials in the case in bins of adjustable size, there are provided a multiplicity of partition members each of which is constructed as shown in Figs. 8 to 10 and includes a vertical wall comprising a generally horizontal portion 24 the lower edge of which conforms to and rests on the horizontal portion 9 of the bottom and a downwardly inclined front portion 25 at its forward end, the lower edge of which conforms to and rests on the downwardly inclined portion 11 of the bottom, while its upper edge conforms to and is located in juxtaposition to the transparent panel 2.

The horizontal portion 24 is provided at its lower edge with a laterally extending flange 26 that rests on the horizontal portion 9 of the bottom wall, and the forward downwardly inclined portion 25 of the partition member is provided at its lower edge with a flange 27 which extends in a direction opposite to the flange 26 and rests on the downwardly inclined portion 11 of the bottom wall. Thus the flanges 26 and 27 support the partition member with its bottom edge conforming to the horizontal portion and the downwardly inclined portion of the bottom wall.

In order to maintain the several partition members in any desired position to vary the sizes of the respective bins, the partition members are selectively adjustable and means provided to hold each partition member securely in any position of adjustment, and the securing means for holding the adjustable partition members will now be described.

At the front of the case there is provided a retaining bar 28 extending endwise of the case and secured in any suitable manner against the vertical wall 13 at the top of the dished portion 12. The retaining bar 28 is provided with a series of vertically extending arcuate recesses or pockets 29, see Fig. 7, and 31 designates a similar retaining bar extending endwise of the case and secured at the rear of the bottom wall 9 against the vertical attaching portion 32 of the rearwardly extending portion 21, and the retaining bar 31 is also provided with a series of arcuate recesses or pockets 33 which are vertically disposed, the curved pockets 29 and 33 at the front and rear of the case acting to hold a partition member in any selected position in which it is arranged, depending upon the size of the bin to be provided.

To effect this, the flange 28 of each partition member, see Fig. 6, is formed at its rear end with an arcuate or curved edge 34 that conforms to the curvature of pockets 33 in the retaining bar 31 and fits therein, the flange 28 being cut away as at 35 forwardly of the retaining bar so that when the partition member has been inserted into locked position at the front of the case, the rear end of the partition member including the curved portion 34 of flange 28 is brought into locking engagement with the selected recess 33 by a downward movement and when flange 28 is resting on the bottom wall of the case, the curved

recess 33 in conjunction with the curved portion 34 on flange 28 prevents lateral movement of the partition member and holds it securely in adjusted position.

5 The partition member is positioned by initially moving its front end forwardly into locking engagement with the retaining bar 28 and for this purpose, the partition member is provided at its forward end with a curved portion 36, see Fig. 9, 10 that conforms to the dished portion 12 and terminates in a horizontal shoulder 37 that underlies the retaining bar 28, and a vertical portion 38 that abuts the inner surface of a recess 29 at its shallowest portion and when the front end of the 15 partition wall is in this position, it is held against lateral movement by the arcuate recess 29.

Each partition member is inserted in any desired position by first moving its front end forwardly until it is interlocked as just described 20 with the retaining bar 28 after which the rear end of the partition member is moved downwardly into locking relation with the retaining bar 31 at the rear of the horizontal portion of the bottom wall, and to remove a partition member, 25 it is first lifted at its rear end, reversing the operation just described.

During positioning or removal of a partition member, the slight upward movement of the rear of the partition member is permitted by the yielding and flexibility of the glass panel 2 and the 30 partition member, very slight pressure being required for the assembling or removal operation, and when in adjusted position, the top edge 39 of the downwardly inclined portion of the partition member is in juxtaposition to or in contact with the inner surface of the inclined glass panel 2. When positioned in the manner described, the 35 partition members are in sufficiently close relation to the front glass panel of the case to hold candy, nuts, or other material within the bin afforded between two partition members which may be positioned to afford any desired width of bin.

With this arrangement, when candy or other 45 material is filled in at the front of the case, the space afforded above the inclined portion 11 of the bottom wall is completely filled up to the top of the partition member, thus affording an attractive display of the contents through the 50 transparent front panel. This display material extends to the top of the partition member, and as the contents of the bin are removed from the rear of the case or from the main body of candy, the level of the contents drops down at the rear 55 of the bin but the candy at the front of the bin overlying the inclined portion 11 of the bottom wall is not affected and holds the body of candy higher at the front to maintain a continued attractive display of maximum extent.

60 This effect is brought about and results from the downwardly inclined portion 11 of the bottom in its relation to the rearwardly and upwardly inclined transparent panel so that the body of candy is maintained to a much higher 65 point at the front of the bin than is possible where the bottom wall is horizontal throughout and the level of the candy remains approximately the same throughout from front to rear as portions are withdrawn. A further advantage of the present structure lies in the fact that when the case is loaded at the beginning of a day, the contents at the front which has previously constituted the display merchandise can 70 easily be mixed with fresh candy and a fresh supply pushed to the front for display purposes 75

so that there is no opportunity for the body of candy used for display purposes becoming stale and wasted as with prior types of display cases where a given amount of candy must always be used for display.

While the invention has been described with reference to the particular construction shown herein, it is not confined to the details disclosed and this application is intended to cover such modifications or departures as may come within the purposes of the improvements and the scope of the following claims.

We claim:

1. A display case including a bottom wall comprising a horizontal portion terminating at its forward end in a forwardly and downwardly inclined portion, supports in different horizontal planes located under the front end of said downwardly inclined portion and the rear end of said horizontal portion, a transparent panel inclined upwardly and rearwardly from the front end of said downwardly inclined portion at an acute angle thereto, a vertical partition member comprising a body portion with its lower edge supported on said horizontal portion of the bottom wall, a forwardly and downwardly inclined forward portion with its lower edge conforming to and supported on said downwardly inclined portion of the bottom wall, the upper edge of said forward portion of the partition member conforming to and located in juxtaposition to said transparent panel whereby said bottom wall, transparent panel, and vertical partition member form a bin the forward end of which inclines downwardly from the rear part of the bin, a flange extending laterally and perpendicularly away from the lower edge of the horizontal portion of the partition member and positionable on the horizontal portion of the aforesaid bottom wall, a flange extending laterally and perpendicularly in the opposite direction away from the lower edge of the downwardly inclined forward portion of the partition member and engaging the aforesaid downwardly inclined portion of said bottom wall, retaining bars extending endwise of the case at the front and rear of the bottom wall and each having a multiplicity of spaced vertically extending recesses, and said partition member being removably engageable with a selected recess in the front retaining bar by a forward movement relatively thereto and having interlocking means at its rear end selectively engageable with a recess in said rear retaining bar by a downward movement relatively thereto.

2. A display case including a bottom wall comprising a horizontal portion having at its forward end a forwardly and downwardly inclined portion terminating in a dished portion, supports in different horizontal planes located under the front end of said downwardly inclined portion and the rear end of said horizontal portion, a transparent panel inclined upwardly and rearwardly from said dished portion at an acute angle to said downwardly inclined portion of the bottom wall, a vertical partition member comprising a body portion with its lower edge supported on said horizontal portion of the bottom wall, a forwardly and downwardly inclined forward portion with its lower edge conforming to and supported on said downwardly inclined and dished portions of the bottom wall and its upper edge conforming to and located in juxtaposition to said transparent panel whereby said bottom wall, transparent panel, and vertical partition

member form a bin the forward end of which inclines downwardly from the rear part of the bin, flanges extending perpendicularly in opposite directions away from the lower edges of the horizontal and downwardly inclined portions of the partition member and positionable on the horizontal and downwardly inclined portions respectively of the bottom wall, a retaining bar extending endwise of the case at the top of said dished portion and having a series of vertically extending transversely arcuate recesses facing inwardly of the case, the partition member having a curved portion at its front end engageable with said dished portion beneath said retaining bar and a vertical edge positionable in one of said recesses, a retaining bar extending endwise of the case in rear of said partition member on said bottom having a series of vertically extending transversely arcuate recesses facing inwardly and said flange on the partition member which extends over the horizontal portion of the bottom having an arcuate portion at its rear end conforming to and positionable within one of said curved recesses of the retaining bar.

3. A display case including a bottom wall comprising a horizontal portion having at its forward end a forwardly and downwardly inclined portion terminating in a dished portion, supports in different horizontal planes located under the front end of said downwardly inclined portion and the rear end of said horizontal portion, a transparent panel inclined upwardly and rearwardly from said dished portion at an acute angle to said downwardly inclined portion of the bottom wall, a vertical partition member comprising a body portion with its lower edge supported on said horizontal portion of the bottom wall, a forwardly and downwardly inclined forward portion with its lower edge conforming to and supported on said downwardly inclined and dished portions of the bottom wall and its upper edge conforming to and located in juxtaposition to said transparent panel whereby said bottom wall, transparent panel, and vertical partition member form a bin the forward end of which inclines downwardly from the rear part of the bin, flanges extending perpendicularly in opposite directions away from the lower edges of the horizontal and downwardly inclined portions of the partition member and positionable on the horizontal and downwardly inclined portions respectively of the bottom wall, retaining bars extending endwise of the case at the front and rear of the bottom wall and each having a multiplicity of spaced vertically extending recesses, and said partition member being removably engageable with a selected recess in the front retaining bar by a forward movement relatively thereto and having interlocking means at its rear end selectively engageable with a recess in said rear retaining bar by a downward movement relatively thereto.
